UNITED STATES PATENT OFFICE.

CHARLES F. OSBURN, OF XENIA, OHIO.

WOOD-CALIPERS.

SPECIFICATION forming part of Letters Patent No. 715,851, dated December 16, 1902.

Application filed February 4, 1901. Serial No. 45,804. (No model.)

To all whom it may concern:

Be it known that I, CHARLES F. OSBURN, a citizen of the United States, residing at Xenia, Greene county, Ohio, have invented a new and useful Improvement in Wood-Calipers, of which the following is a full and exact specification thereof.

My invention relates to an improvement in an instrument called "wood-calipers," and is used by carpenters and wood-lathers.

The object of my improvement is to provide a new and ready means for adjusting the parts of the device to suit the requirements of the user.

For a more complete description I refer to my drawings hereto attached and made a part of the specification.

In the drawings like numerals refer to corresponding parts.

Figure 1 shows the machine looking down upon its top. Fig. 2 shows the back part of the device. Fig. 3 shows a full side view.

The machine is preferably made of iron or any other metal suitable, and the main frame (shown by I and I') is all cast in one piece and shaped as shown in the drawings, I' being the main body, and I the circular arm extending from the main body. This circular arm I has toward its end and on its inner side an extension or point 7, the use of which will be hereinafter explained. The main body I' is cast with a square hole through its entire length, and in this square hole is placed

a piece of steel 2, which has cog-notches on its one side and a chisel-point at its lower end, (designated by 6.) It will be observed that at the one side of I' is left a space in which a roller 3, having spiral threads, is placed, and this spiral-thread roller is held in place by the bolt 5, which also serves as an axis 40 upon which the roller is revolved by the operator. The spiral threads upon the roller 3 engage the cog-notches of the steel piece 2, and thus by turning the roller it causes the steel piece 2 to be moved up and down in the frame in which it works and is easily adapted to be moved to suit the convenience of the user.

Having described my invention, what I claim is—

In a device of the class described, a body or shank having a semicircular arm at one end thereof with an inwardly-extending point 7 in line with said body, a slide passing through a channel in said body and having a pointed end 6 in opposition to said point 7, said slide having a toothed edge, a screw 3 journaled in a cut-away portion of said body and engaging said teeth and a set-screw threaded into an opening in the shank and adapted to clamp said slide, substantially as described.

CHARLES F. OSBURN.

In presence of—

W. L. MILLER,
C. S. HARRIS.
